UNITED STATES PATENT OFFICE.

ARTHUR E. COLGATE, OF NEW YORK, N. Y., ASSIGNOR TO GEORGE J. SCHOFFEL, OF BROOKLYN, NEW YORK.

ELECTRICAL VALVE-CONTROLLING DEVICE.

SPECIFICATION forming part of Letters Patent No. 605,197, dated June 7, 1898.

Application filed May 28, 1896. Renewed April 1, 1898. Serial No. 676,136. (No model.)

To all whom it may concern:

Be it known that I, ARTHUR E. COLGATE, a citizen of the United States, residing at New York city, in the county and State of New York, have invented a certain new and useful Improvement in Electrical Valve-Controlling Devices, of which the following is a specification.

This invention is an improvement upon the electrical whistle or valve controlling devices described in Letters Patent No. 553,900, issued February 4, 1896, which devices are mainly designed for use on ships. In that patent is shown an automatic circuit-controller for operating a steam-whistle consisting of an electric motor driving a rotating circuit-breaker, (constituting an automatic controller,) a magnet for controlling the supply of current to said motor, and a hand-switch for permitting the operation of the whistle at will. In my present arrangement I employ a clock-movement as the automatic circuit-controller for the whistle and a modified form of magnet for controlling the circuit to the clock-movement and an improved weatherproof hand-switch for controlling the apparatus at will, and by means of a modified form of hand-switch the controlling-magnet is in some cases dispensed with.

My invention is illustrated in the accompanying drawings, in which—

Figure 1 is a diagrammatic view of one form of controlling apparatus; Fig. 2, a similar view of the form in which the controlling-magnet is dispensed with; Fig. 3, an elevation of the weatherproof switch for controlling the apparatus at will; Fig. 4, a vertical central section of the same, showing the switch-contacts arranged for the form of apparatus illustrated in Fig. 1. Fig. 5 is a plan view of the switch-plate employed with the arrangement of switch-contacts shown in Fig. 4. Figs. 6, 7, and 8 are detail views of the switch-contacts employed with the arrangement illustrated in Fig. 2; and Fig. 9 is a view of the interior of the hood employed with the switch.

Referring to Fig. 1, A indicates the steam-whistle, whose valve is operated by electro-magnet A'. This magnet is controlled automatically by a circuit-controlling clock B

and controlled at will by the hand-switch C through a relay D. The details of construction of the hand-switch are illustrated in Figs. 3 to 9, inclusive. The valve-operating magnet A' is shunted by a high-resistance shunt-circuit containing sparking-points A² and a resistance A³, which may be an incandescent electric lamp. The object of this shunt-circuit is to receive the discharge from the magnet A' when the circuit is opened at either the clock or hand-switch. The circuit connections are as follows: from binding-post 1 by wire 2 to armature D' of relay D, contact 3, wire 4 to automatic switch in clock B, from said switch by wire 5 to binding-post 6 through magnet A' to binding-post 7 and wire 8 to binding-post 9. The batteries E or the circuit-wires from some other source of current-supply are connected to binding-posts 1 and 9. The circuit connections just indicated include the automatic controller B, and with the connections so established in practice the circuit to magnet A' would be closed periodically by the automatic controller B and operate the whistle on each closure of the circuit. To operate the whistle at will, the switch C is moved so that switch-plate g will bridge the contacts 10 and 11, thus closing the shunt-circuit 12 13 to relay D. The relay becoming energized attracts its armature, which makes contact with stop 14, closing the shunt 15 and cutting out the automatic controller.

In the arrangement illustrated in Fig. 2 the relay D is dispensed with and a three-contact switch is employed. The circuit connections are as follows: from binding-post 1 by wire 2 to binding-post 3, through magnet A' to binding-post 4 and wire 5 to binding-post 6, from binding-post 6 through the automatic switch in clock B to binding-post 7, wire 8 to terminal 9 of hand-switch C and contact-plate g to terminal 10, wire 11 to binding-post 12, and wire 13 to binding-post 14. The batteries E or the circuit-wires from some other source of current-supply are connected to the binding-posts 1 and 14. The circuit connections, as indicated, represent the automatic controller in circuit to close the circuit to magnet A' periodically. To remove the

automatic controller from the circuit, the disk *f* is turned by the switch-handle in the direction indicated by the arrow until switch-plate *g* is in contact with terminal 10 only, which leaves the circuit open entirely. Further movement of the switch places switch-plate *g* in contact with terminals 10 and 15, closing the circuit direct to the whistle. A further movement of the disk *f* carries switch-plate *g* onto contacts 9 and 15, which opens the battery-circuit entirely, and the whistle-valve will remain closed until the switch-plate *g* is moved backward onto contacts 10 and 15 to blow the whistle for a signal or forward onto contacts 9 and 10, placing the automatic controller into circuit again to blow the whistle periodically, as in a fog.

The hand-switch, which is designed to be weatherproof, is illustrated in detail in Figs. 3 to 9, inclusive, in which *a* is a circular body, having a flange *a'*, provided with screw-holes whereby the switch is supported. Into the circular body *a* is screwed a hollow cylindrical body *b*, which when the parts are assembled is held against removal by a screw *b'*. Within the body *b* is a circular base *c* of insulating material, into which the contact-posts *d* are screwed, as shown in Fig. 4. The base *c* is slotted at *c'* to engage a lug on the inside of body *b* to hold the base against rotation and so that the contact-posts carried by it will have a definite position with relation to the switch-plate. The lower ends of posts *d* are provided with hollow heads, into which circuit-terminals are inserted, as will be hereinafter stated.

Through the upper part of the cylindrical body *b* passes a spindle *e*, carrying at its lower end a disk *f*, of insulating material, provided with a switch-plate *g*, adapted to make contact with the ends *d'* of the contact-posts *d*, which project through the insulating-body *c*. The lower end of the spindle *e* preferably passes through the insulating-base *c*, and a pin *e'* passes through the spindle and serves to hold together the parts described to enable those parts to be readily assembled with the remaining parts of the switch. The part of the spindle *e* which passes through the base *c* is preferably reduced so as to form a shoulder, and the head *c* is capable of slight vertical movement on the spindle *e*, so as to permit the contacts to better adjust themselves when the parts of the switch are assembled, and when assembled the base *c* is firmly held in position between the shoulders *b'* and *a'* of the bodies *a* and *b*. The disk *f* is loosely carried on the spindle *e* and held from rotation by a spline *c'*. A coiled spring *h*, seated between the disk *f* and the collar *e'* on the spindle, serves to maintain the switch-plate in close contact with the ends *d'* of the contact-posts *d*.

The bearing in the upper end of the chamber *b* through which the spindle *e* passes is made water-tight by rubber packing-rings *i* and *i'* and a packing-ring *i''*. The joints be-

tween the bodies *a* and *b* are made water-tight by two rubber packing-rings *a''*.

The circuit-wires are formed into a heavily-insulated cable *x*, which passes through the shell *x'*, into the upper end of which is seated a base *x''*, of insulating material, secured in position by a screw *x'''*. The wires from the cable pass through holes in the insulating-base to binding-posts *y* and *y'*, which are connected, respectively, with the circuit-terminals *z* and *z'*. These circuit-terminals are split rods adapted to fit into the hollow heads of the contact-posts *d*, as shown in Figs. 4 and 6. The portion of the cable which extends through the shell *x'* is wrapped with insulating-tape *x''*, and the entrance of the cable is made water-tight by a rubber packing-ring *x'''* and cap *x''''*. The shell *x'* is secured to the main body portion *a*, and terminals *z* and *z'* are forced into contact with posts *d* by a screw-collar *x''''*, screwing onto the screw-threaded extension *a''* of the body *a*, the collar *x''''* having a flange *x'''''* engaging with the shoulder of shell *x'*. Between the end of the extension *a''* and a shoulder within the collar *x''''* is placed a packing-ring *x''''''*.

To prevent the entrance of water around the spindle *e*, the spindle is provided with a hood *k*, which is seated upon a shoulder formed at the upper end of the spindle *e* and firmly secured in place by a nut *k'*, a water-tight joint being formed between the spindle *e* and hood by means of white lead. To turn the spindle in operating the switch, a handle *l* is provided, which has a screw-threaded end *l'* screwed into the base of the hood, and the end of the screw-threaded portion *l'* enters a recess in the spindle, as shown in Fig. 4, so that the spindle will turn with the handle and so that the handle and switch-plate *g* will have definite positions when the switch parts are assembled. To prevent the handle *l* working loose, I provide a set-screw *l''*. The hood *k* is provided with ribs *k''*, forming notches *k'''* and *k''''*. A spring-plate *m*, secured to the lower end of the body *b*, engages with these notches and serves to hold the switch in the various positions to which it may be set. The spring-plate *m* is preferably V-shaped in cross-section, so that the notches *k''''* may be readily disengaged to permit the turning of the switch.

The construction of the switch employed with the two forms of apparatus illustrated in Figs. 1 and 2 is practically the same, the only difference being that in the arrangement shown in Fig. 1 two contact-posts are employed, while in the other form three contacts are employed. Fig. 6, however, illustrates a further modification, which may also be employed in the two-contact switch. This difference consists in making the contact-posts *d* hollow at both ends and inserting spring-pressed contact-buttons *d''* in the upper ends, with which the switch-plate *g* makes contact. In this arrangement the head *f*, carrying the switch-plate *g*, is rigidly secured

to the spindle *e* by means of a pin *f*'. The arrangement of contact-buttons illustrated in Fig. 6 permits the contact-buttons to adjust themselves against the switch-plate and insure perfect contact.

5 What I claim is—

1. The combination with a valve, of a magnet for controlling the same, a circuit extending thereto, an automatic circuit-controller for periodically opening and closing said circuit, and a single hand-operated switch for controlling the operation of the valve at will and also for controlling the connection of the automatic controller with the valve-magnet circuit, substantially as set forth.

15 2. The combination with a valve, of a magnet for controlling the same, a circuit extending thereto, an automatic circuit-controller for periodically opening and closing said circuit, a magnet for cutting said automatic controller out of circuit, and a single hand-operated switch for controlling the operation of the valve at will and also for controlling the operation of said last-named magnet to connect 25 or disconnect the automatic controller in circuit, substantially as set forth.

3. The combination with a valve, of a magnet for controlling the same, a circuit extending thereto, an automatic circuit-controller for periodically closing said circuit, and a hand-switch having three contacts and a contact-plate adapted to bridge one pair of said contacts to place said automatic controller in the magnet-circuit to periodically open and 35 close said circuit and to bridge another pair of said contacts to close the magnet-circuit at will, and which contact-plate assumes intermediate positions at which both the automatic controller is cut out of circuit and the 40 magnet-circuit is opened, substantially as set forth.

4. In a weatherproof electrical switch, the combination with a cylindrical and practically water-tight casing, of a set of contacts 45 within the casing carried by a base of insulation, a rotating switch-plate adapted to make contact with said set of contacts, a spindle projecting through the casing for rotating said switch-plate, said plate and set of contacts being adapted to move relatively to each other in a direction lengthwise of the spindle, a hood on said spindle extending over the top

of the switch-casing, and a handle for rotating the spindle, substantially as set forth.

5. In a weatherproof electrical switch, the 55 combination with a cylindrical and practically water-tight casing, of a set of contacts within the casing carried by a base of insulation, a rotating switch-plate adapted to make contact with said set of contacts, a spindle 60 projecting through the casing for rotating said switch-plate, said plate and set of contacts being adapted to move relatively to each other in a direction lengthwise of the spindle, a hood on said spindle extending over 65 the top of the switch-casing, a handle for rotating the spindle, and means coöperating with said hood for holding the spindle in its various positions, substantially as set forth.

6. In a weatherproof electrical switch, the 70 combination with a practically water-tight casing, of a series of contacts within said casing carried by a stationary base of insulation, a rotating switch-plate adapted to make contact with said series of contacts, a spindle 75 projecting through the casing for rotating said switch-plate, said switch-plate and said series of contacts being adapted to move relatively to each other in a direction lengthwise of the spindle in addition to the relative movement of rotation, and an operating-handle for 80 said spindle, substantially as set forth.

7. In an electrical switch, the combination with a stationary base of insulation carrying a series of spring-seated contacts, of a rotating switch-plate adapted to make contact with said series of contacts, a spindle for rotating said switch-plate, said series of contacts being held in intimate contact with said switch-plate by the springs upon which they 90 are seated, sockets carried by said stationary base of insulation, contact-posts adapted to enter said sockets, said sockets and contact-posts being arranged to permit slight movement toward and away from each other without breaking contact, and an operating-handle for said spindle, substantially as set forth. 95

This specification signed and witnessed this 22d day of May, 1896.
